HULLER GIN

Jeffrey J. Wallace, Amite, La., assignor to Gul-
lett Gin Company, Amite, La., a corporation of
Louisiana

Application January 24, 1939, Serial No. 252,633

5 Claims. (Cl. 19—56)

This invention relates to huller gins. It is an improvement upon a gin of the type disclosed in my Patent No. 2,142,977, granted January 3, 1939, which has an inner ginning breast and an outer huller breast, forming between them a roll box, each breast having a grating of ribs with the gin saws passing between both sets of ribs so that the saws act first upon the cotton, which is introduced into the huller breast, drawing it through the huller ribs with the seeds, but to the substantial exclusion of the hulls, and then acting upon the roll of cotton and seeds which forms in the roll box, to draw the lint through the ginning ribs to the exclusion of the seeds which are discharged downwardly between the two sets of ribs.

The roll of the cotton in the roll box finally becomes so overburdened with trash, hull particles, seeds, etc. that it becomes necessary to dump the roll from the roll box. In my aforementioned patent, the inner or ginning breast is pivoted at its upper end to the gin, and the outer or huller breast is pivoted at its upper end to the inner breast. Thus, both breasts can be swung out as a unit at the bottom, to cause the withdrawal of the saws from between both sets of ribs, and when it becomes necessary to dump the roll box, the outer breast can be swung out independently of the inner breast, enlarging the space between the two sets of ribs so that the roll can drop downwardly through the passage thus formed. The primary purpose of swinging both breasts out as a unit, so as to withdraw the saws, is to clear the ribs of accumulated matter, as well as to get access to the saws for their replacement or repair. It is advantageous, however, to have the breasts separated from the gin at the time the outer breast is separated from the inner breast to dump the roll box, for the saws are then out of the path of the discharged roll.

In my patent, means are provided for separating both breasts at the bottom from the gin, and for separating the outer breast at the bottom from the inner breast, and for holding them in separated positions.

One of the disadvantages of a construction in which the huller breast is pivotally connected at its top to the ginning breast is that the passage which it provides when spread, for the roll, is narrow at the top so that the roll does not always drop out automatically, but often has to be started by poking it with a stick.

The general object of the present invention is to avoid this disadvantage by substituting for the swinging movement of the outer breast a bodily

translatory movement that shall separate the outer breast from the inner breast substantially uniform both at the top and at the bottom, so as to provide a passage for the discharge of the roll which is much wider at the top than in the case of an outer breast which operates by separating pivotally from the inner breast. In this connection, reference is here made to my pending application, Ser. No. 259,033, filed February 28, 1939, which discloses an outer breast movable in a translatory manner with respect to the inner breast.

Another object of the invention is the provision of means for effecting the separation of the outer breast from the inner breast by bodily translatory movement both at the top and at the bottom, and maintaining the outer breast in such separated position.

Other objects of the invention will appear as the following description of a preferred and practical embodiment thereof proceeds.

In the drawings which accompany and form a part of the following specification, and throughout the several figures of which the same characters of reference have been employed to designate identical parts:

Figure 1 is a side elevation of a huller gin embodying the features of the present invention showing the inner and outer breasts in closed position; and

Figure 2 is a similar view showing the breasts in spread or separated position.

Before referring in detail to the figures, it may be stated that only such features of the huller gin as directly appertain to the present improvement are hereinafter referred to, and that those unskilled in the art who may require a more detailed exposition of gin construction for an understanding of the invention, are referred to my Patent No. 2,142,977, in which the more detailed explanation of the inner parts may be found.

The huller gin of the present invention includes the fixed frame 1, which carries the saw shaft 2 with the saws 3. The inner breast 4 is pivotally mounted upon the frame 1 at 28, and normally rests against the frame 1, as shown in Figure 1. The outer breast 5 co-operates with the inner breast to form a roll box, the rotary end plate of which is indicated at 6 in Figures 1 and 2. Most of the roll box is defined within the walls 50 of the inner breast, but the face 7 of the outer breast forms the outer wall of the roll box. There is normally a narrow passage from the roll box downward between the breasts for the passage of seed, when the outer breast 5 is in the closed

position shown in Figure 1. The saws 3 normally intersect this narrow passage cooperating with both breasts. Both the inner and outer breasts can be swung away from the fixed frame 1 so as to withdraw the saws from the passage between the breasts. This swinging movement is accomplished by means of a toggle comprising the two links 9 and 10 pivoted together at 11, and having their opposite ends 12 and 13 pivoted, respectively, to the fixed frame and to the inner breast. A hand lever 14 operates this toggle. It being assumed that the inner breast 4 is in closed position with respect to the frame 1, the toggle is in the folded position indicated in Figure 1. When the hand lever 14 is thrown in a clockwise direction, the toggle straightens out as shown in Figure 2, spreading the inner breast at the bottom, from the gin.

Instead of the upper pivotal connection for the outer breast, as employed in the huller gin disclosed in my said patent, the end plates of the inner breast are provided with the track flanges 15, which are preferably upturned at both ends. The end plates of the outer breast 5 are formed with lugs 16 carrying rollers 17 which ride upon the track flanges. Thus, the outer breast rides bodily in or out with respect to the inner breast for a range of distance represented by the length of the track flanges 15. The forward upturned ends 18 of said track flanges constitute stops to limit the outward movement of the upper end of the outer breast 5. The movement of the upper part of the outer breast is produced by toggles, one on each side of the gin, each comprising the two links 19 and 20 which are pivoted at their adjacent ends at 21 and at their outer ends, respectively, to the inner breast at 22, and to the outer breast at 23, the latter pivot preferably being the axis of the rollers 17. When this toggle is in folded position, the upper part of the outer breast is at its extreme limit of outward movement. When this toggle is straightened, as shown in Figure 1, the rollers 17 have been forced to the innermost limits of their range of movement, and the upper part of the breast is in closed position.

The means for opening and maintaining open the lower part of the outer breast are same as in my Patent No. 2,142,977, said means comprising a toggle consisting of the cooperating links 23' and 24 pivoted at their adjacent ends at 25, and at their opposite ends, respectively, to the inner breast at 26 and to the outer breast at 27. When said toggles are in folded position, as in Figure 1, the bottom of the outer breast is closed. When this toggle is in straight position, as in Figure 2, the bottom of the outer breast is in open position relative to the inner breast.

Means are provided for synchronizing the opening and closing movements of the toggles at the top and bottom of the outer breast. Said means in the present illustrative embodiment of the invention comprises a link 29 connecting the middle pivots of the toggles on one side of the gin. A hand lever 31 operates the lower toggle, and through the intermediary of the link 29, also operates the upper toggle so that when the lower toggle is straightened to separate the bottom of the outer breast from the inner breast, the upper toggle is broken in order to separate the upper part of the outer breast from the inner breast. It will be understood that the pivots 12 and 26 to which the respective handle levers 14 and 31 are secured, are in fact rods extending to the opposite sides of the gin, and which operate duplicate sets of toggles, such as have just been described.

It will be evident from an inspection of Figure 2 that by means of the track and roller connection between the outer and inner breasts as hereinbefore disclosed, or by the employment of equivalent mechanical means for accomplishing the bodily separation of the two breasts at the top, as well as at the bottom, the front face of the roll box is moved away from the portion of the roll box embraced within the inner breast a much greater distance than is possible with any pivotal connection, and amply wide to assure the automatic discharge of the roll from the roll box.

While I have in the above description disclosed what I believe to be a preferred and practical embodiment of the invention, it will be understood to those skilled in the art that the details of construction and the arrangement of parts as shown and described, are to be considered by way of example, and not as limiting the invention which is defined in the appended claims.

What I claim is:

1. Huller gin including a fixed frame carrying saws, inner and outer breasts cooperating to form a roll box, said inner breast being movably mounted upon said frame so as to permit withdrawal of the saws from said breasts, said outer breast being mounted on said gin for bodily translatory movement away from said inner breast, and means for separating said outer breast from said inner breast both at the top and bottom, and for maintaining it thus separated.

2. Huller gin including a fixed frame carrying saws, inner and outer breasts cooperating to form a roll box, said inner breast being movably mounted upon said frame so as to permit withdrawal of the saws from said breasts, said outer breast being mounted on said gin for bodily translatory movement away from said inner breast, and means for synchronously separating said outer breast from said inner breast both at the top and bottom, and for maintaining it thus separated.

3. Huller gin including a fixed frame carrying saws, inner and outer breasts cooperating to form a roll box, said inner breast being movably mounted upon said frame so as to permit withdrawal of the saws from said breast, said outer breast being mounted on said gin for bodily translatory movement away from said inner breast, and means for separating said outer breast from said inner breast both at the top and bottom, and maintaining it thus separated, said means including a track and roller connection between said outer and inner breasts, at the top, and an operating toggle pivoted at its outer ends to said inner and outer breasts, and acting to spread the breasts at the top, the roller moving upon the track, the latter being formed with a stop to limit the separation of the breasts.

4. Huller gin including a fixed frame carrying saws, inner and outer breasts cooperating to form a roll box, said inner breast being movably mounted upon said frame so as to permit withdrawal of the saws from said breast, said outer breast being mounted on said gin for bodily translatory movement away from said inner breast, and means for synchronously separating said outer breast from said inner breast both at the top and bottom, and maintaining it thus separated, said means including a track carried by said inner breast on both sides at the top, and rollers correspondingly carried by said outer breast movable upon said tracks, upper and lower operating toggles on both sides of said breasts pivotally mounted at their outer ends to said

breasts and functioning to spread said breasts both at the top and bottom, and a connection between said toggles for synchronizing their operation.

5. Huller gin including a fixed frame carrying saws, inner and outer breasts cooperating to form a roll box, said inner breast being movably mounted upon said frame so as to permit withdrawal of the saws from said breast, said outer

breast being mounted on said gin for bodily translatory movement away from said inner breast, and means for separating said outer breast from said inner breast both at the top and bottom, and for maintaining it thus separated, said means comprising toggles between said breasts adjacent the top and bottom and means interconnecting said toggles for operating them together. 5

JEFFREY J. WALLACE.
